UNITED STATES PATENT OFFICE

2,504,225

FOLDING BOAT

Benjamin F. Randrup, San Francisco, Calif.

Application October 14, 1946, Serial No. 703,153

8 Claims. (Cl. 9—2)

1

This invention relates to improvements in folding boats.

An object of my invention is to provide a foldable boat easily collapsed and folded into a compact form for convenience in handling, storage and transportation.

Another object of my invention is to provide a new and improved portable folding boat having a simple and durable construction, more especially designed for use by fishermen, campers, hunters and others, and arranged to fold into compact form for convenience in transportation over land or by automobile, and also arranged to be quickly set up when its use is desired.

A further object of my invention is to provide a folding boat of the kind characterized having a sturdy construction which permits the carrying of a heavy load in rough waters without danger of collapsing or capsizing.

This invention is an improvement on the folding boats disclosed in my Letters Patent No. 2,346,081, issued April 4, 1944 and No. 2,408,579 issued October 1, 1946.

Other and further objects of my invention will be pointed out hereinafter, indicated in the appended claims, or will be obvious to one skilled in the art upon an understanding of the present disclosure. For the purpose of this application I have elected to show herein certain forms and details of a folding boat representative of my invention; it is to be understood, however, that the embodiment of my invention herein shown and described is for the purpose of illustration only, and that therefore it is not to be regarded as exhaustive of the variations of the invention.

In the accompanying drawings:

Fig. 1 is a top plan view of a folding boat embodying the principles of my invention;

Fig. 2 is a bottom plan view of the same;

Fig. 3 is a side perspective view of the same;

Fig. 4 is a top perspective view of the same;

Fig. 5 is a diagrammatic view showing the relative positions of those parts making up the boat's rear end portion;

Figs. 6, 7, 8, and 9 are sectional views taken on the lines as indicated in Fig. 1;

Fig. 10 is an enlarged sectional view taken

2

transversely through the keel portion of the boat; and

Fig. 11 is an enlarged detail view showing the means joining a side and bottom members.

Referring to the drawings the numerals 1 and 2 designate two elongated bottom members which are flexibly connected together along their adjacent longitudinal side edges by an intervening strip 3 of waterproof fabric, such as canvas. The waterproof strip 3 is secured to the bottom members at their upper sides by riveted battens 4 or other suitable means. The flexible strip 3 is secured as by rivets 5 between a longitudinal keel member 6 and an overlying member 7. The keel member 6 is normally engaged at its opposite sides by the inner longitudinal side edges of the bottom members 1 and 2 (see Fig. 10). Secured to the strip 3, as by rivets, are longitudinally arranged battens 8 which overlie the battens 4. Underlying the keel member 6 and secured thereto as by the rivets 5, is a rigid lower member 9 which provides a support for the inner edges of the bottom members 1 and 2. The lower member 9 also provides protecting means for normally preventing damage to the keel portion of the boat when landings are made. The lower member being arranged with its lateral edges protruding outwardly for considerable distances from the keel member, normally prevents the side slipping of the boat. The bottom members are preferably made from flat panels of plywood or other suitable material, and each is somewhat triangular in shape, but provided with an upwardly curved lower forward edge which terminates at a pointed forward end. When the boat is set up and the various parts are in assembled cooperating positions, the bottom members 1 and 2 at their rear ends are slightly inclined in opposite directions from the keel portion, but proceeding forwardly they gradually assume positions of increased inclination while at the same time they gradually curve outwardly, upwardly and forwardly to form compound bends or slightly convex surfaces at points adjacent but rearwardly of a pointed bow 10.

Flexibly connected to the outer edges of the bottom members 1 and 2, respectively, are substantially triangular shaped elongated side members 11 and 12. The adjacent edges of the bot-

tom and side members are connected together by waterproof strips 13, and a substantially flat longitudinal member 14 (Fig. 11) riveted to each of the said strips provides protecting means therefor. The flexible strips 13 are secured to the inner surfaces of the side and bottom members by riveted or otherwise suitably attached battens 15. The side and bottom members when in unfolded and set up positions are arranged so that the lower edge of each side member rests on its associated bottom member. The particular battens 15 which are secured to the bottom members 1 and 2 provide abutments to prevent the lower edges of the side members from engaging with the flexible strips 13. Such a flexible connecting means for the bottom and side members is well protected from damage from the outside as well as from the inside, and it still permits the folding of the members one upon another in a satisfactory manner.

The stern of the boat comprises a flexible end member 16 of waterproof material such as canvas, having a substantially rectangular shape. The lateral and lower edges of the flexible end member 16 is secured to the bottom members 1 and 2 and to the side members 11 and 12 by riveted, glued or otherwise secured battens or other suitable means.

Hinged to the rear end of the side member 11 is a rigid rear panel 17 which is of sufficient length to extend approximately, but not entirely, across the rear end of the boat. Hinged to the rear end of the side member 12 is a rigid rear panel 18 which is also of sufficient length to extend approximately, but not entirely across the rear end of the boat. The panel 17 has a substantially vertical shoulder 17' near its hinged end with which the free end of the panel 18 engages, and similarly the panel 18 is provided with a substantially vertical shoulder 18' which is engaged by the free end of the panel 17. When setting the boat up the free end of the rear panel 17 is brought into engagement with the shoulder 18' of the panel 18 and the latter is then swung rearwardly to a position against the said rear panel 17, thereby drawing the flexible rear member 16 taut. The rear panels 17 and 18 are adapted to fold against the said members 11 and 12, respectively. When in extended positions the rear panels 17 and 18 are preferably secured together by suitable means, as by bolt 19 and a nut 20, the bolt being provided with a hooked end which is passed through slots in the said panels and then turned cross wise to a position where it engages with a bar 19a secured to the rear side of the panel 17 before the wingnut is applied to clamp the rear panels together.

A rigid end panel 21 hinged as by a canvas strip 22 to the upper edge of the rear panel 18 is adapted to be swung rearwardly to a position at the rear of the flexible rear member 16. At the free edge of the end panel 21 is secured metal members 21' which are adapted to engage with clips 23 secured at the rear ends of the bottom members 1 and 2, thereby normally maintaining the said end panel in fixed parallel relationship with respect to the rear panels 17 and 18. The end panel 21 protects the flexible rear member 16 and provides rigid means for mounting an outboard motor at the stern end of the boat. A metal plate 21a secured centrally to the outer side of the rear end panel 21 provides means for preventing damage to the exposed surface of the said panel when an outboard motor is mounted thereon.

Extending across the interior of the boat in engagement with the side and bottom members are a plurality of rigid U-shaped ribs or frame members 24 which are held against displacement by pairs of opposed members 24' secured to the member 7 of the keel structure and the side members 11 and 12. The outer ends of the frame members 24 underlie horizontal U-shaped channel members 25 secured as by rivets to the side members 11 and 12, and the said outer ends are normally in engaging relation with respect to the said channel members. Seats 26 are removably supported in the channel members 25, and at the rear end of the boat another seat is supported by cleats secured to the side members 11 and 12. The seats 26 may be prevented from shifting forwardly or rearwardly as by pins extending through aligned holes in the channel members, the seat and the frame members.

20 A centrally disposed vertical brace 27 is positioned at the rear end of the boat with its rear end firmly engaging with the rear panel 18 and its forward end held against forward displacement by a hooked bar 28 fastened to the overlying member 7 of the keel portion of the boat, the said hooked bar engaging with a keeper 29 secured to the forward end of the brace (Fig. 9). The rear end of the brace 27 is provided with a bracket member 30 having an opening at its upper end through which the bolt 19 extends, the said bolt being arranged for preventing the lateral displacement of the said brace.

25 At opposite sides of the boat, on the side members 11 and 12, are mounted sockets 31 for holding oar locks in operative positions.

30 The forward end of the boat is provided with a concave cowl which comprises two semi-rigid cowl sections 32 which are joined together by hinges. The lateral edges of the cowl sections curve inwardly and are arranged in adjacent or engaging positions with respect to the upper edges of the forward ends of the bottom and side members 11 and 12. The lateral edges of the cowl sections are engaged by and are normally held against displacement with respect to the bottom and side members 11 and 12 by inwardly bent lugs 33 secured to the upper edges of the bottom and side members 11 and 12. A board 34 hinged to the forward U-shaped frame member 24 underlies the rear ends of the cowl sections 32, the said board having an arcuate upper edge which is adapted to engage with the under side of the cowl sections to hold them in upwardly bent positions forming a concave cowl.

35 A canvas covering 35 extends around the pointed bow of the boat and over the forward apex of the cowl. Wooden strips 36 are secured to the rear portions of the bottom members 1 and 2 for preventing damage thereto when the boat is dragged from the water.

40 A ring 37 secured to the bow of the boat provides means for attaching a mooring line.

45 When the boat is to be collapsed for convenience in carrying, storage or handling, the cowl is first detached by swinging the board 34 downwardly to a disengaging position with respect to the cowl sections 32. When the tension or holding pressure on the cowl sections has thus been removed they are easily disengaged from the lugs 33 and lifted from the forward end of the boat. The seats 26 are next detached. The bolt 19 is then removed from an engaging position with respect to the end panels 17 and 18 and the bracket member 30 of the brace 27, following which the end panel 21 and the rear panels are

swung outwardly to positions adjacent the side members 11 and 12.

The U-shaped frame members 24 are removed, thereby permitting the said members 11 and 12 to be folded inwardly against the bottom members 1 and 2, respectively. The bottom members 1 and 2 together with their connected side members are then folded inwardly toward each other. By reason of the flexibility of the side and bottom members whatever curvatures they had when in set up positions will no longer remain after the various pressures are removed. Owing to the novel manner in which the various parts are arranged and connected together the time required to assemble the structure into an operable boat is but a few minutes. The particular manner in which the various pressures are distributed and applied to the assembled parts gives the boat a rigidity comparable to that of an uncollapsible type of boat, while at the same time there are no damaging strains or stresses present which are apt to weaken the structure at any point.

What I claim is:

1. In a folding boat, a pair of elongated bottom members flexibly connected longitudinally along adjacent side edges, two elongated side members flexibly connected to the outwardly disposed longitudinal edges of the bottom members, the said side members each being arranged to fold upon its associated bottom member rigid frame members for holding the side and bottom members in unfolded relationship, rear end panels hinged to and foldable upon the side members, the said rear end panels when unfolded being arranged to extend across the rear end of the boat, a flexible rear end member enclosing the rear end of the boat, and a substantially rigid protector hinged to one of the end panels and arranged to be positioned externally against the rear surface of the flexible end member.

2. In a folding boat, a pair of elongated bottom members flexibly connected longitudinally along their adjacent side edges, two elongated side members flexibly connected to the outwardly disposed longitudinal edges of the bottom members, the said side members each being arranged to fold upon its associated bottom member, rigid frame members arranged to hold the side and bottom members unfolded, a flexible rear end member enclosing the rear end of the boat, a rigid foldable rear end structure positioned forwardly of and adjacent the flexible rear end member, and a substantially rigid protector hinged to the rigid end structure and arranged to be positioned against the rear surface of the flexible end member.

3. In a folding boat, a pair of elongated bottom members flexibly connected longitudinally along their adjacent side edges, two elongated side members flexibly connected to the outwardly disposed longitudinal edges of the bottom members, the side members each being foldable against its associated bottom member, a plurality of rigid frame members interposed between the side and bottom members for maintaining them in unfolded positions, a flexible rear end member secured to the bottom and side members for enclosing the rear end of the boat, a rigid panel hinged to and foldable against each side member, the said panels being arranged to extend across the rear end of the boat in a position forwardly of the flexible rear end member, the said panels each having a shoulder adjacent its hinged end arranged for engagement by the free end of the other panel when the

panels are positioned across the rear end of the boat, whereby the flexible rear end member may normally be maintained in a taut position.

5. In a folding boat as defined by claim 3, including a rigid protector hinged to one of the panels and arranged to extend transversely alongside the rear surface of the flexible rear end member.

10. 5. In a folding boat, a pair of elongated bottom members flexibly connected longitudinally along their adjacent side edges, two elongated side members flexibly connected to the outwardly disposed longitudinal edges of the bottom members, the side members each being foldable upon its associated bottom member, a plurality of rigid frame members interposed between the bottom and side members for maintaining them in unfolded position, a cowl detachably secured to the forward ends of the side members, the said cowl having a plurality of sections foldable one upon another, and closure means for the rear end of the boat.

6. In a folding boat, a pair of elongated bottom members flexibly connected longitudinally along their adjacent side edges, two elongated side members flexibly connected to the outwardly disposed longitudinal edges of the bottom members, the side members each being foldable against its associated bottom member, a plurality of rigid frame members for holding the side and bottom members in unfolded positions, means closing the rear end of the boat, a plurality of foldable joined sections detachably mounted on the forward end of the side members, the said sections forming a cowl extending over the forward end of the boat, and a rigid member arranged inside the boat for holding the joined sections in unfolded concave formation.

7. In a folding boat, a pair of elongated bottom members flexibly connected longitudinally along their adjacent inner side edges, two elongated side members flexibly connected to the outer edges of the bottom members, the said bottom members being arranged to form a pointed bow, a plurality of rigid frame members interposed between the bottom and side members for holding them in unfolded positions, a plurality of joined foldable sections forming a pointed cowl extending rearwardly from the pointed bow and arranged to overlie the forward interior portion of the boat, means for detachably securing the lateral edges of the cowl to the upper exposed edges of the forward ends of the side and bottom members, rigid means for normally holding the joined sections of the cowl in unfolded relation when they are in extended positions overlying the forward interior portion of the boat, and means connected to the side and bottom members for enclosing the rear end of the boat.

8. In a folding boat a pair of elongated bottom members flexibly connected longitudinally along their adjacent inner side edges, two elongated side members flexibly connected to the outer edges of the bottom members, the said bottom members being arranged to form a pointed bow, a plurality of rigid frame members interposed between the side and bottom members for maintaining them in unfolded positions, a plurality of joined flexible sections forming a pointed cowl extending rearwardly from the pointed bow and arranged to overlie the forward interior portion of the boat,

means for detachably securing the lateral edges of the cowl to the upper exposed edges of the forward ends of the side and bottom members, a pivoted member connected to one of the frame members and arranged to engage with and exert an upward pressure on the rear end portions of the cowl sections, whereby the said sections may be maintained in upwardly curved relationship, and means enclosing the rear end of the boat.
